US0D1048022S

(12) **United States Design Patent** (10) Patent No.: **US D1,048,022 S**
(45) Date of Patent: ** Oct. 22, 2024

(54) **ELECTRONIC DEVICE**

(71) Applicant: **Amazon Technologies, Inc.**, Seattle, WA (US)

(72) Inventors: **Quinn Huffstetler**, San Francisco, CA (US); **Christopher Clive Jones**, San Francisco, CA (US)

(73) Assignee: **Amazon Technologies, Inc.**, Seattle, WA (US)

(**) Term: **15 Years**

(21) Appl. No.: **29/787,945**

(22) Filed: **Jun. 9, 2021**

(51) LOC (14) Cl. **14-02**

(52) U.S. Cl.

USPC **D14/434**; D23/364

(57) **CLAIM**

The ornamental design for an electronic device, as shown and described.

DESCRIPTION

FIG. 1 is a front, top, right-side perspective view of an electronic device;

FIG. 2 is a back, bottom, left-side perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dashed broken lines depict portions of the electronic device that form no part of the claimed design. The dot-dashed broken lines depict a boundary of the claim and form no part of the claimed design.

1 Claim, 8 Drawing Sheets
